UNITED STATES PATENT OFFICE.

WALTER T. GODDARD, OF VICTOR, NEW YORK, ASSIGNOR, BY MESNE ASSIGNMENTS, TO
GARTON-DANIELS COMPANY, OF KEOKUK, IOWA, A CORPORATION OF IOWA.

LIGHTNING-ARRESTER.

No. 882,673.

Specification of Letters Patent. Patented March 24, 1908.

Application filed August 7, 1905. Serial No. 273,134.

To all whom it may concern:

Be it known that I, WALTER T. GODDARD, a citizen of the United States, residing at Victor, in the county of Ontario and State 5 of New York, have invented new and useful Improvements in Lightning - Arresters, of which the following is a full, clear, concise, and exact description, reference being had to the accompanying drawing, forming a part of 10 this specification.

My invention relates to protective appliances for protecting electrical apparatus from the destructive effects of lightning discharges and excessive currents in light and 15 power circuits.

A particular object of my invention is to so mount the different parts of the protective apparatus that the current passing through the same will not find outside paths and will 20 not flash off between the current carrying parts and damage the device.

Difficulty has been experienced in former types of lightning arresters or protective devices, due to the collection of dust or the condensation of moisture upon the base upon 25 which the several parts are mounted, which provide outside paths over the surface of the base, which the static discharge or the normal current in some cases would follow in preference to its intended path through the conducting parts of the arrester. When the current flashes off between these parts, due to 30 the above mentioned causes, it short-circuits various parts and frequently results in serious 35 damage to, if not a destruction of, the arrester, as well as the grounding of the line with which the arrester or protective appliance is connected. I have particularly designed 40 my present invention to overcome these objections, and have so mounted the various parts of the protective appliance that I am enabled to secure a maximum surface distance on said base between the parts thereon which are liable to differ greatly in potential, 45 whereby the tendency of short-circuits is reduced to a minimum.

There are other features of my invention which will be more particularly described in the accompanying specification.

50 I have illustrated the preferred form of my invention in the accompanying drawings, in which

Figure 1 is a front elevation of my protective apparatus; Fig. 2 is a side elevation

thereof; and, Fig. 3 is a sectional view of the 55 mounting for the operating magnet.

In the practical construction of my device, upon the upper end of an insulating base 1, which is preferably formed of slate or other like insulating material, is mounted a 60 bracket 2, having a binding post 3, to which the line wire may be connected and provided with a discharge point 4, preferably in the form of a metal cylinder having a semi-spherical end and suitably secured and supported in the bracket 2, by means of the set screw 3^a. Beneath this discharge point is mounted a resistance rod 5, having secured on the upper end thereof a discharge point 6, which is also preferably formed of metal and 70 has a semi-spherical end. The discharge points 6 and 4 have a slight air gap between the same, as shown in the drawing. The resistance rod 5 may take any suitable form, but I prefer to construct the same in the 75 form of a graphite rod and in order to obtain an increased surface distance on the base between the current carrying parts of the arrester, which rest on the base and are liable to differ greatly in potential I have provided 80 upon the base near the lower end of the resistance rod 5, a small plate having an outwardly projecting lug 7, to which is attached by means of a screw 10 the inner end of a metallic supporting band 9, which surrounds the resistance rod. The extreme 85 lower end of the resistance rod is also supported by a similar band 11, which is connected to an outwardly projecting lug 12, of a plate screwed or otherwise secured to the 90 insulating base 1. This plate has a projection 13, which lies upon the underside of the resistance rod to prevent a vertical movement thereof, and is also provided with a 95 projection to which is attached the flexible conductor 15, for a purpose which will more fully appear hereinafter. By thus providing the support or mounting for the resistance rod 5, at the lower end thereof, I am enabled 100 to arrange the support for the resistance rod 100 at the greatest possible distance from the bracket 2.

At a point upon the base, near the lower end of the resistance rod 5, and to one side thereof, is mounted a support 16, in which is 105 secured the fiber tube 17. This support consists of a head having a socket 18 formed therein, in which is fitted the upper end of

the fiber tube 17. The upper end of the socket is preferably made wider, as at 19, and an annular wedge 20 on the inside of the tube 17, tends to spread the upper end there-
5 of to hold the same securely in position and prevent the tube from dropping. A magnet coil 21 is carried upon and surrounds the tube 17, and is adapted to actuate a core 22 located within the tube and capable of mov-
10 ing longitudinally therein. The core 22 carries a rod 23 extending from its upper end and out at the top of the tube, and through the support 16, being connected with the end of the conductor 15. This rod is preferably
15 or brass, although other material may be used.

A discharge point 24, preferably formed of metal and having a semi-spherical end, is adapted to fit within the lower end of the
20 fiber tube, and is secured in position therein by means of a pin 25, passing therethrough and through the tube. Mounted upon the upper end of the discharge point 24, within the tube 17, is a carbon button 26. Im-
25 mediately beneath the discharge point 24 is mounted a bracket 27, similar to the bracket, 2, having a binding post 28, whereby the same may be connected with the ground con-
30 ductor, and carrying the discharge point 29,
35 which is secured in position in the bracket by the set screw 30. The discharge point 24 and discharge point 29 are separated from each other by a small air gap, as shown in the drawing.

35 One terminal of the coil 21 is connected by a conductor 31, with the lug 7, and the opposite terminal of the coil is connected by conductor 32, with the projection 12, whereby the coil is connected in shunt of the lower
40 portion 34 of the resistance rod 6. It will be seen that with the devices and circuit connec-
5 tions shown, a current has two paths to earth, namely, through the entire resistance
45 5, solenoid core directly to the part 24 and also through a portion of the resistance 5 through the solenoid and through the solen-
50 oid core to the part 24.

In operation, a lightning or similar dis-
50 charge on the line wire will seek the path from the bracket 2; across the air gap be-
55 tween the discharge points 4 and 6, and, be-
cause of the impedance of the solenoid winding
21, will not divide at the supporting band
5, by the conductor 15, through the core 22,
55 thence jumping across the air gap to elec-
trode 29, and thence to the ground. As soon
60 as the arc is established across the spark gap,
a comparatively low resistance path for the
line current is furnished and it at once fol-
65 lows the path in a large volume and being
continuous in character, will divide by reason
of the resistance between the connections 9
and 11 and a portion thereof will pass
through the magnet 21 by way of conductors

31 and 32. The magnet or solenoid will be-
come energized, drawing up its core and lift-
ing the same from contact with the carbon
button 26, thus opening the circuit and stop-
ping the flow of current in the branch from
70 the line through the instrument to the
ground. The flow of current being stopped,
the arc between the electrodes 24 and 29
ceases, so that upon the falling of the core,
as soon as the magnet is deenergized, the cir-
75 circuit will again be open at the electrodes and
the instrument in position to act in the same
way upon the occurrence of another dis-
charge.

It will be noted with particular reference to my invention that the danger of short circuits due to dust or moisture or both combined on the surface of the base is lessened by mounting the different parts as above described to obtain a large increase of surface
85 distance between the current-carrying parts resting on the base, between which there is likely to exist a great difference of potential and by reference to the drawings it will be seen that this surface distance is from the
90 lower edge of the bracket 2 to the upper edge of the band 9, and from the lower edge of the band 11 to the upper edge of the bracket 27.

While I have described one form of my in-
vention, it will be understood that various
95 modifications may be made without depart-
ing from the spirit of the invention as set
forth in the appended claims.

Having thus described my invention what
I claim as new and desire to secure by Let-
100 tens Patent is:

1. In a lightning arrester, the combination with a suitable insulating base, of binding posts near the ends of said base, an operating magnet, a tube of insulating material carry-
105 ing said magnet and having arranged within the same the core of said magnet, and a single supporting means for said tube near its upper end upon the base.

2. In a lightning arrester, the combination with an insulating base, of an operating mag-
net, an insulating tube carrying said magnet and having the core of said magnet arranged within the same, a discharge point carried at
115 one end of said tube, a discharge point con-
nected with the ground mounted beneath
said first mentioned discharge point, and a single supporting means for the tube ar-
ranged upon said base at the end of the tube
farthest from the discharge points.

3. In a lightning arrester, the combination with an insulating base, of a resistance, a binding post mounted on said base near one end of said resistance, and a single support-
125 ing means arranged near the other end of said resistance farthest away from the binding post for supporting said resistance upon the base, so that a large surface distance is interposed on said base between said sup-
porting means and said binding post.

4. In a lightning arrester, the combination with an insulating base, of a discharge point connected with the line and mounted upon said base, a resistance, a second discharge point mounted at one end of said resistance coöperating with said first mentioned discharge point, and a low resistance supporting member arranged near the other end of said resistance farthest away from the discharge point connected with the line, so that a large surface distance is interposed between said low resistance member and said discharge point connected with the line.
5. In a lightning arrester, the combination with an insulating base, of a discharge point carried thereby adapted to be connected with the line, of a resistance, a discharge point coöperating with said first mentioned discharge point and carried by one end of said resistance, and single means positioned near the other end of said resistance for supporting said resistance upon said base.
6. In a lightning arrester, the combination with an insulating base, of a discharge point carried thereby, a resistance, a discharge

point coöperating with said first mentioned discharge point and carried at one end of said resistance, a single supporting means for said resistance near its opposite end, an operating magnet, an insulating tube carrying said magnet, and having arranged therein the core of the magnet, and means for supporting said tube near its upper end.

7. In a lightning arrester, the combination with an operating magnet, of an insulating tube supporting the same and carrying at one end a discharge point, a resistance having one end thereof adjacent one end of said tube, a discharge point carried upon the opposite end of said resistance, and means for supporting respectively, at their adjacent ends said resistance and said tube.

In witness whereof, I have hereunto subscribed my name in the presence of two witnesses.

WALTER T. GODDARD.
